United States Patent

Des. 237,432
Patented Nov. 4, 1975

237,432

MULTI-SHELVED FLOOR STAND DISPLAY OR SIMILAR ARTICLE

Ronald H. Taub, Highland Park, Ill., assignor to Taub Family Trust

Filed Apr. 29, 1974, Ser. No. 465,104

Term of patent 14 years

Int. Cl. D20—02

U.S. Cl. D6—23

FIG. 1 is a perspective view of a multi-shelved floor stand display or similar article, showing my new design;

FIG. 2 is a side elevational view thereof;

FIG. 3 is a top plan view thereof; and

FIG. 4 is a bottom plan view thereof.

I claim:

The ornamental design for a multi-shelved floor stand display or similar article, as shown.
